UNITED STATES PATENT OFFICE.

MILTON E. BUCK, OF EMATON, KANSAS.

WIRE-REEL.

1,299,550.

Specification of Letters Patent.

Patented Apr. 8, 1919.

Application filed June 10, 1918. Serial No. 239,270.

To all whom it may concern:

Be it known that I, MILTON E. BUCK, a citizen of the United States, residing at Ematon, in the county of Stevens, State of Kansas, have invented certain new and useful Improvements in Wire-Reels; and I do hereby declare the following to be a full, clear, and exact description of the invention, such as will enable others skilled in the art 10 to which it appertains to make and use the same.

This invention relates to improvements in reeling and unreeling devices and particularly to devices for reeling and unreeling 15 fence wire.

One object of the present invention is to provide a novel and improved device of this character which can be easily and quickly attached to the rear end of a farm wagon 20 and turned to unwind the wire as the wagon moves forwardly.

Another object is to provide novel and improved means whereby the device can be easily and effectively operated to wind the 25 old fence wire when the same has been removed from the fence.

A further object is to provide a novel and improved construction of device of this character whereby the filled spool of wire, 30 or the spool to receive the wire can be easily and quickly placed on or taken from the device.

Other objects and advantages will be apparent from the following description when 35 taken in connection with the accompanying drawing.

In the drawing:

Figure 1 is a side elevation of the device shown in connection with the rear portion 40 of a farm wagon.

Fig. 2 is a top plan view of the same, the wagon being broken away.

Fig. 3 is a rear elevation of the device.

Fig. 4 is an enlarged vertical sectional 45 view taken on the line 4—4 of Fig. 1.

Fig. 5 is a vertical longitudinal sectional view taken on the line 5—5 of Fig. 2.

Referring particularly to the accompanying drawing, 10 represents the body of a farm wagon and 11 the rear axle thereof, 50 in connection with which my invention is used. Engaged over the rear axle are the forward hook ends 12 of two rearwardly extending bars or links 13, vertical pins 14 being disposed through said hook ends rearwardly of the axle to hold said links in en-

gagement with the axle. Secured to the rear end of each of the links is a two part bearing member 15, the same being held together by means of the bolts 16. Rotatably 60 mounted in each of these bearings is a spindle 17, the other end of which is secured within one end of a tubular shaft or axle 18. Rotatably supported on this shaft is a drum 19, and carried by one end of the drum and 65 rotatable therewith is a ground engaging wheel 20. Pivotedly mounted on the other end of the drum are the spokes 21, the outer ends of which are detachably connected, by means of the bolts 22, to the apertured lugs 70 23 of the felly 24, said parts coöperating, when properly engaged with each other to form the other ground engaging wheel of the cart.

Pivotedly connected to each of the links 13 75 is a section 25 of a brace member, the other portion 26 being slidably connected therewith and having its other end engaged over the upper edge of the end gate 27 of the wagon. These sections of the braces are 80 adapted to be adjusted longitudinally with respect to each other to permit the ground wheels to engage with the ground in one instance, and to hold the cart in elevated position so that the wheels will not touch the 85 ground.

When it is desired to apply the wire spool 28 on the drum, the bolts 22 are removed and the spokes 21 swung on their pivots until they lie in an extended position longitudinally from the end of the drum, and in such position that the spool can be readily slipped thereover. It will, of course, be understood that the adjacent bearing is opened 90 to release the spindle carried thereby, so 95 that the link can drop down to the ground, and thus be out of the way when the spool is lifted to be slipped onto the drum. Then, as the wagon is driven forwardly, the wheels of the cart will be turned so that the drum 100 will turn and cause the unwinding of the wire on the spool.

When the device is used for reeling old fence wire which has been removed from the posts, the wheels of the wagon are fixed by 105 blocks so that the wagon will not move, and the braces 25—26 adjusted so that the cart is lifted from the ground, then the fixed wheel of the car is turned to rotate the drum, the wire being first secured at one end thereto. 110

What is claimed is:

1. A wire reeling and unreeling device in-

cluding a wheeled cart, members carried by the cart for detachable connection with the axle of a wagon, a rotatable drum on the cart, the said wheels being carried by the 5 ends of the drum and rotatable therewith, the spokes of one of the wheels being detachable from the felly thereof and foldable to extend longitudinally from the end of the drum to permit the application of a wire 10 spool on the drum.

2. A wire reeling and unreeling device including a pair of links each having a hook member engaged with the axle of a wagon, bearings on the other ends of the links, spindles rotatable in the bearings, a shaft car- 15

ried by the spindles and detachable therefrom, a drum rotatable on the shaft, a ground engaging wheel fixed on one end of the drum, spokes movably mounted on the other end of the drum and arranged to be 20 folded to permit the application of a spool on the drum, and a felly detachably connected to the outer ends of the movably mounted spokes.

In testimony whereof, I affix my signature, in the presence of two witnesses.

MILTON E. BUCK.

Witnesses:

Mrs. E. R. EDWARDS,
Ross M. LEASE.
